UNITED STATES PATENT OFFICE.

BRITTON E. BYRD, OF DURHAM, NORTH CAROLINA, ASSIGNOR TO MILL DEVICES COMPANY, OF DURHAM, NORTH CAROLINA, A CORPORATION OF NORTH CAROLINA.

KNOTTER DEVICE.

Application filed February 24, 1922. Serial No. 538,889.

To all whom it may concern:

Be it known that I, BRITTON E. BYRD, a citizen of the United States, and resident of Durham, in the county of Durham and 5 State of North Carolina, have invented certain new and useful Improvements in Knotter Devices, of which the following is a specification.

This invention relates to a knot tying 10 method and mechanism and more particularly to a method and mechanism for tying small flat knots known as the "weaver's knot"; and has special reference to the provision of a novel knot tying device or knotter 15 capable of forming and tying a "weaver's knot" in an exceedingly simple manner with the employment of relatively simple mechanism.

In a variety of operations employed in 20 textile mills it is common to tie the ends of two threads or strands together in a small flat knot known in the art as the "weaver's knot". For tying these ends with facility and rapidity a number of mechanisms have heretofore been suggested and 25 devised, these prior mechanisms employing various methods of manipulating or handling the threads and of forming the knot therein. While a number of mechanisms 30 have been suggested and designed to this end, they have not been extensively adopted in practice, the prior knotters of this type known to me being impractical or unwieldy in service from an operating viewpoint, es- 35 pecially when employed as a hand operated knotter, some of these mechanisms involving too complex an organization with too many working parts, while others involve too tedious and cumbersome a method of 40 threading the knotter prior to operating the same. Where in prior devices the mechanism itself has been simplified by minimizing the number of working parts and their correlation, this has been usually accom- 45 plished at the expense of ease of thread manipulation by the operator, that is at the expense of ease of threading of the strands in the knotting device prior to operating the same, the manner of threading or posi- 50 tioning the strands in the knotter in such devices having been made a relatively difficult operation in itself. Where the knotter has been constructed to receive the threads in a "logical" manner such as with the

strands or threads arranged in substantially 55 parallel relation, the mechanism devised has been found generally too complex for effective operation and efficient use. To provide a weaver's knotter in which simplicity of organization is combined with ease of 60 threading is a principal object of my present invention.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my 70 invention, and in which:

Figure 1 is a right side view of the weaver's knotter showing the manner of using the same where the knotting device is constructed in the form of a hand operated knotter,

Figure 2 is a top plan view of the same, 75 Figure 3 is a front view of the same, Figure 4 is a left side view of the knotter, Figure 5 is a cross sectional view of the 80 same showing some of the interior working parts,

Figures 6 to 13 are views showing the sequence of steps of both the operating and operated parts of the knotter during knot 85 forming and tying, and

Figure 14 is a view of the resulting weaver's knot obtained.

Before describing my knotter in detail I will briefly relate the method I employ in 90 making the weaver's knot and the mechanism I prefer to use in forming and tying the same. The threads or strands to be tied which may, for example, be two separated strands coming from a spool and bobbin re- 95 spectively, are first arranged in substantially parallel relation, this being the first "logical" step in manipulating threads. The threads are then crossed at spaced points, the crossing of the threads being either ef- 100 fected simultaneously or at different times. One of the strands or threads is then twisted 180 degrees about one crossing to provide a loop in the thread, the twisting being effected about the second strand, the second strand being thereby threaded through the loop, after which both threads are again 105 rotated through an angle about 180 degrees.

effecting a twist in the first loop and effecting an embryo loop in the second thread which embryo loop is thereafter formed into a complete loop, the end of the strand of this second loop being thereafter threaded through the two loops formed, resulting in the weaver's knot. Referring to Figures 3, 8, 10, 11, 13 and 14, I show the essential operated parts of the mechanism and the manner in which these parts are operated to effect the formation of the loops and the tying of the threads into a weaver's knot. The two strands in threading the knotter, are first laid over oppositely positioned thread guide and holding means designated respectively as A and B, these guide and holding means being so arranged with respect to a tying bill mechanism C of a well known type that one of the strands such as s' is positioned below the tying bill mechanism C and the other of the strands such as s² is positioned above the said tying bill mechanism, the tying bill mechanism being thus positioned or located between the two strands. Reference to Figure 3 will disclose the simplicity of threading the knotter presented with this arrangement. After the strands or threads are received by the knotter in substantially parallel relation, as shown in Figure 3, the strands s' and s² are crossed at two spaced points such as x' and x², this crossing being preferably effected by mechanism forming part of the guide and holding means A and B respectively, as will be disclosed more in detail hereinafter. Figure 8 shows the arrangement of the strands after this operation and the arrangement of the operated elements of the knotter with the strands so crossed. After the strands are crossed the tying bill mechanism C is then rotated in the direction as shown by the arrow in Figure 8 of the drawings so that the bills of the tying bill mechanism move between the strands s' and s² beyond the first crossing x'. After rotating the tying bill mechanism through an angle of substantially 180 degrees a loop L' is formed in the strand s' with the strand s² threaded through the loop, this being clearly shown in Figure 10 of the drawings. After this formation is obtained the tying bill mechanism is further rotated through another angle of about 90 degrees, the arrangement of the strands relative to the tying bill mechanism being such that during this rotation one of the bills of the tying bill mechanism moves through the crossed strands beyond the second crossing x² and the strand s² is grasped by the tying bill mechanism C, this being clearly shown in Figure 10 of the drawings. In the further rotation of the tying bill mechanism C through another angle of about 90 degrees the strand s² is cut and clamped by the tying bill mechanism as is common in these devices, and

during such rotation an auxiliary cutter D is brought into play for cutting and clamping the strand s', the parts of the mechanism being so relatively arranged that the strands will be cut relatively to the knot to be tied in a manner to obtain thread ends of equal length. Figure 11 shows the relative arrangement of the parts of the mechanism and the loop formations in the knot in a position during the rotation of the knot tying mechanism C during this last mentioned 90 degree movement. After the knot tying mechanism C has terminated its movement during this last angle of rotation the loop formations of the strands or threads on the knot tying mechanism assume the configuration as shown in Figure 13 of the drawings. Referring to this figure, the strand s' is shown with its previously formed loop L' twisted through 180 degrees and the strand s² provided with a portion beginning at or near the grasped end thereof and encircling the bill and forming an embryo loop L². The strands s' and s² coming from the spool and bobbin are then pulled for stripping the loop formations from the tying bill mechanism C as is common in such devices, this stripping effecting first the completion of the loop L² and then the threading of the clamped end of the thread s² through the loop formations L' and L² in the threads s' and s², the resulting knot obtained after this stripping operation having a configuration as shown in Figure 14 of the drawings, this being the well known form of weaver's knot. Referring now in detail to the drawings, for supporting the parts of the knotter I provide the left side plate 10 and the right side plate 11, the latter being provided with a foot portion 12 terminating in a reduced toe portion 13, the said toe portion being fittingly received by a slot 14 in the plate 10, these parts being effective for spacedly supporting the side plate 10 on the side plate 11. For securing the plates in spaced position I preferably provide the locking screw 15 received in a suitably tapped aperture in the toe 13, the locking screw abutting against the outer walls of the side plate 10 for locking the parts together. Connecting the side plates 10 and 11 at a region spaced from the foot 12 I provide the U shaped bracket member 16, the lower branch of this bracket member being provided with oppositely extending flange portions 17 and 18; the said flange portions being adapted to be received by sockets or recesses 19 and 20 respectively provided in the side plates 10 and 11. For securing the side plates together at this region I provide the bolt 21 arranged preferably between the two branches of the U bracket 16. For the purpose of adapting the knotter as a hand operated device I provide the handle or grip member generally designated as 22, the

said handle or grip member comprising a palm portion 23 adapted to seat on the palm of the hand of an operator, an end portion 24 bent at an angle thereto and a supporting arm portion 25 made preferably integral therewith; the said supporting arm portion 25 being attached to the side plate 10 as by means of the securing screws 26. The handle 22 is also provided with the adjustable strap 27 as is common in these devices. If preferred, the handle 22 may be made integral with the side plate 10 and the parts bent into the desired configuration from a single piece of sheet material.

15 The tying bill mechanism C which comprises the bill shaft 28, the clamping bill 29, the cutting bill spring 30 and the intermediate shearing and clamping jaw 31, is rotatably mounted in the knotter supporting means and to this end the bill shaft 28 is journaled in the foot portion 12 and the bracket 16. This is shown particularly in Figures 5 or 9 of the drawing, and referring to these figures the bill shaft 28 is 20 provided at its lower end with a spindle portion 32 received by and rotatable within a bushing 33 fitted in the foot 12, a flanged sleeve 34 being provided at the upper end of the bill shaft 28 and connected to the bill shaft for journaling the latter in an orifice 35 in the lower branch of the U bracket 16. The shearing and clamping jaw 31 is provided as is usual in these devices with a lower wing portion 36 movable within 25 an enlarged aperture 37, the said aperture being provided in the upper branch of the U bracket 16 and being arranged eccentrically to the bearing orifice 35 and acting as a cam track to effect the oscillation of 30 the shearing and clamping jaw 31 during the rotation of the tying bill mechanism; the said clamping jaw 31 being mounted for oscillation on the bills 29 and 30 as by means of the pivot pin 38. The flanged sleeve 34 is preferably slotted at its upper end for receiving the lower portion of the jaw wing 36, guiding of the said shearing and clamping jaw 31 during its oscillation being thereby effected. In the present form of my invention I prefer to curve the bill portions 29 and 30 and the bill of the clamping jaw 31, this to the end of permitting easier stripping of the knot therefrom.

35 The thread guide and holding means A in the present form of my invention is constructed and designed to perform a number of independent functions. During threading of the knotter the said thread guide and holding means A is intended to provide 40 guide means for receiving in spaced relation the two strands to be knotted. During operation of the knotter the thread guide and holding means performs the function of crossing the thread to effect the first crossing & therein, the threads being clamped 45 by the thread guide and holding means, the latter at a subsequent step, as will be described more in detail below, effecting the stripping of the threads from the tying bill mechanism after the formation of the knot. 70 For performing these various functions the thread guide and holding means A comprises essentially the guide arm 39 and the thread engaging member 40, the guide arm and member being arranged for relative movement and being pivoted to the opposite ends of a lever 41 as by means of the pivot pins 42 and 43 respectively. The guide arm 39 is provided with a guide head 44 and the latter is, in turn, provided with spaced guide slots 45 and 46, the former being inset relatively to the latter to position the two strands to be knotted in different planes. The thread engaging member 40 comprises 75 a U shaped lever fulcrumed by the pivot pin 43, the two upwardly disposed branch arms of the U lever comprising thread engaging arms 47 and 48, the said arms straddling the guide arm 39 and being slidably movable relatively thereto. For effecting the relative slidable motion between the guide arm 39 and the branch engaging arms 47 and 48 I provide the guide head 44 with a struck up pin portion 49, the latter received by and movable within a longitudinal slot 50 provided in the inner branch arm 48. The lower portion of the thread engaging member 40 comprises a suitably contoured follower arm 51, the lower end of this arm being adapted to ride over and be guided by cam track portions 52 and 53 of a directing guide piece 54, the latter being secured to the side plate 10 as by means of the securing screws 55. The lever 41 carrying the guide arm 39 and the thread engaging member 40 is fulcrumed on a main cam shaft 56 journaled in the opposed plates 10 and 11, the lever 41 being provided with a sleeve portion 57 pinned to the cam shaft 56 for rotation therewith. Upon rotation of the cam shaft 56 counterclockwise as viewed in Figure 4, the guide arm 39 and thread engaging member 40 slidably move in opposite directions, the slidable motion being directed by means of the follower arm 51 riding upon the guide track 52, the said parts being constrained to slidable movement by means of the pin and slot connection 49 and 50. During this relative movement of the guide arm and the thread engaging means the thread engaging means is adapted to engage the thread arranged in the guide slot 45 and move the same past the thread held in the guide slot 46. To this end the opposite branch arms 47 and 48 are provided with thread engaging fingers 58 and 59 so arranged relatively to the bottom of the guide slot 45 as to engage the thread therein and move the same into 100 crossed relation with respect to the thread 105 110 115 120 125 130

in the guide slot 46, this being particularly shown in, for example, Figure 8 of the drawings, the thread s' being here shown clamped between the branch arms 47 and 48 and the guide arm 39 and moved to crossed position relative to the thread s^2 . During this motion the thread s^2 is also engaged by a thread engaging finger for confining the thread in the guide slot 46, the branch arm 48 being to this end provided with a second thread engaging finger 60. Figure 8 of the drawings, for example, shows the manner in which the thread s^2 is confined in the guide 46 by means of the thread engaging finger 60. For the purpose of adjusting the clamping action of these parts on the thread s' , the pivot pin 43 is made to comprise an adjusting screw, rotation of which changes the clamping action of the branch arms 47 and 48 of the thread engaging member 40. With the provision of this recited construction it will be apparent that during a partial rotation of the main cam shaft 56 equal to the traveling distance of the arm 51 over the cam track 52, the threads or strands s' and s^2 will be crossed and the thread s' clamped in crossed position. The motion of these parts for obtaining these functions is effected, as will become clearer hereafter, prior to the rotation of the tying bill mechanism C. After the threads are arranged in crossed position the tying bill mechanism C is rotated with the tying bills moving between the strands or threads beyond the first crossing x' as referred to hereinbefore, rotation of the tying bill mechanism C through an angle of about 270 degrees effecting the formation of the loops shown in Figure 10 of the drawings, the tying bill mechanism C then being brought into cooperation with the thread guide and holding means B.

The thread guide and holding means B also is designed to effect a plurality of functions such as the receiving of the threads during the threading of the knotter, crossing the threads and confining the same in desired positions. The said thread guide and holding means B to these ends comprises a guide head 61 and a thread engaging member 62 slidably movable relatively thereto. The guide head 61 is provided with the spaced guide slots 63 and 64, one offset relatively to the other, for receiving the separated strands to be tied. These guide slots may be of a construction similar to the guide slots of the thread guide and holding means A and similar means may be provided for effecting the crossing of the threads. However, in the present form of my construction I prefer to so contour the guides 63 and 64 as to automatically effect the crossing of the threads during guiding activity. This is made possible by reason of the fact that the thread ends received in the guides

63 and 64 are manipulated by the operator. To this end the guide slot 63 is provided with a horizontal portion for receiving the thread s' and a slot portion 65 arranged substantially longitudinally of the head 61 and cut to a depth to effect the movement of the thread s' past the thread s^2 in the guide slot 64, as will be clearly apparent from a consideration of, for example, Figures 8 and 10 of the drawings. The thread engaging member 62 is provided with the thread engaging fingers 66 and 67 cooperating with the guide slot 64 and 65 for confining the strands or threads therein. The thread engaging member 62 is slidably mounted on the side plate 11 and to this end the member 62 is provided at its lower end with a slot 68 receiving a pin 69 anchored to the side plate 11, the guide head 61 being suitably slotted as at 70 for spacedly guiding the upper portion of the thread engaging arm 62. As will be apparent from a consideration of the drawings, the guide head 61 is preferably made integral with the side plate 11 and is offset relatively thereto, these parts being suitably stamped out of a single piece of sheet material. For moving the arm 62 into thread engaging position I provide the said arm with a cam portion 71 provided with a cam slot 72 and cooperating with the cam slot I provide a cam follower 73 journaled in the end of an arm 74, the latter being pinned to the main cam shaft 56. The cam slot 72 is contoured so that upon rotation of the cam shaft 56 the thread engaging member 62 will be rapidly moved in position to cooperate with the guide slots 63 and 64 to confine the threads therein, this being obtained by the cooperation of the cam follower 73 with the horizontal portion 75 of the cam slot 72. This movement of the member 62 corresponds in extent to the movement of the thread guide and holding means A heretofore described. With the provision of this construction, referring now to Figure 10 of the drawings, it will be apparent that the thread ends of the strands s' and s^2 are crossed and spread apart to permit the bills of the tying bill mechanism C to move therebetween, the thread or strand s^2 being grasped between the jaw and bills of the tying bill mechanism during such movement, the said strand s^2 being cut and clamped by the tying bill mechanism C as is customary in these devices, this being shown in Figure 11 of the drawings. During this latter movement of the tying bill mechanism C as heretofore recited the auxiliary cutter D is brought into play for effecting the cutting and clamping of the thread s' .

The auxiliary cutter D of my invention comprises the spaced clamping blade 76 and cutting blade 77 and the cutting and clamping jaw 78 movable therebetween and ful-

crummed thereon by means of the pivot pin 79. The blade 77 preferably comprises a spring member attached to the blade 76 as by means of an adjusting screw 80 (see Figures 2 and 5 for example) adjustment of the said screw being provided for effecting changes in the clamping action of the said cutting device. This auxiliary cutter D is arranged relative to the other parts of the 10 knotter so as to permit the unhindered rotation of the tying bill mechanism C, the cutting mechanism D being brought into play for grasping and cutting the thread s' after the tying bill mechanism C has moved past 15 the same. The auxiliary cutter D is therefore given a compound motion first to bring the same into the seat of action and adjacent to the tying bill mechanism C and second, to cut and clamp the end of the thread s' . 20 To operate the parts of the auxiliary cutter to effect this compound motion I provide the following mechanism. The blade 76 of the cutter is fulcrumed on the main cam shaft 56 and the lower portion of the 25 said blade is provided with a cam track 82. Pivotally connected to the cutting and clamping jaw 78 I provide the link 83, the said link pivotally connecting the jaw to a cam plate 84 also rotatably arranged on the 30 main cam shaft 56. In the normal position of the parts the cutting mechanism is arranged as shown in Figure 5 of the drawings and out of the path of movement of the tying bill mechanism C. After the tying bill 35 mechanism C has assumed the position shown in Figure 10 of the drawings the clamping blade 76 and the cam plate 84 are moved by means to be described in detail hereinafter so as to move the cutting 40 mechanism bodily into position between the tying bill mechanism C and the thread guide and holding means B, the cutting and clamping jaw 78 being then moved relatively to the blades 76 and 77 to effect the 45 cutting and clamping of the thread s' , as clearly appears in Figure 13 of the drawings.

After the rotation of the tying bill mechanism into the position shown in Figure 13 50 of the drawings and the formation of the loops thereon with the thread termini cut and clamped respectively by the tying bill mechanism C and the auxiliary cutter D, the threads s' and s^2 coming from the spool 55 and bobbin are then stripped from the tying bill mechanism C, the stripping effecting the tightening of the knot formed in the threads and the stripping of the knotted threads from both the tying bill mechanism 60 and auxiliary cutter. For effecting the stripping operation I may provide independent stripping means. However, in the present form of my invention I utilize part of the apparatus already described for effecting 65 the stripping function. More specifically, I so construct the thread guide and holding means A as to effect this desired function. This latter is shown in Figure 12 of the drawings and referring to this figure it will be found that after the thread guide arm 70 39 and the thread engaging member 40 have served their functions in crossing and clamping the threads the said thread guide 39 and thread engaging member 40 are caused to rotate bodily or substantially as a unit 75 about the cam shaft 56, such rotation effecting the tightening and stripping of the threads from the tying bill mechanism C and the auxiliary cutter D. For directing and guiding this movement the cam track 53 80 heretofore recited cooperates with the fol- lower arm 51 of the thread engaging mem- ber 40. The side plate 10 is further pro- vided with a struck up guide stop 85 act- ing as a stop for the thread engaging mem- 85 ber 40 in the return of the parts to normal position.

All the parts of the mechanism hereto- 90 fore described are operated by means of a single element adapted to be actuated by the thumb of the operator if the device is to be used as a hand knotter. To this end I pro- 95 vide the operating thumb lever 86 fulcrumed on the side plate 10 and movable about the screw shaft 87, a tortion spring 88 having one end hooked over the operating arm 89 of the thumb lever 86 and having the other end anchored to the side plate 10 being pro- 100 vided for effecting the return of the thumb lever 86 and the parts operated thereby to normal position. For effecting the rotation 105 of the tying bill mechanism C the bill shaft 28 of the said tying bill mechanism is preferably constructed in the form of a helix 90, the said helix being obtained by twisting a piece of sheet material and for cooper- 110 ating with the helix 90 the operating arm 89 is forked at its outer end to provide the fork members 91 and 92; the said fork members straddling the helix and rotating the same during operation of the thumb lever 86. With the provision of this construction the operating arm 89 may be made to control the movement of other parts of the mechanism and the helix may be de- 115 signed to permit prior and subsequent move- ment of other parts of the mechanism before and after the rotation of the tying bill mech- 120 anism C. Thus, when the fork members 91 and 92 are positioned as shown in Figure 3 of the drawings the said fork members may be moved for a considerable distance prior to effecting the rotation of the tying bill mechanism C. Similarly, as shown in 125 Figure 9 of the drawings, after the tying bill mechanism C has been rotated substan- tially 360 degrees the fork members 91 and 92 may be moved longitudinally of the bill shaft 28 without effecting further rotation of the tying bill mechanism C. Thus, with 130

the provision of this construction the parts may be reduced in number and may be made to cooperate effectively.

- For effecting the operation and the various functions of the thread guide and holding means A, I provide a cam plate 93 pinned to the main cam shaft 56 as by means of the pin 94. The cam plate 93 is provided with three cam portions 95, 96 and 97 and cooperating with these cam portions I provide the cam follower 98 rotatably journaled on the end of the fork member 92 of the main operating arm 89. With the provision of this construction it will be apparent that upon movement of the thumb lever 86 the cam follower 98 will move in the cam grooves 95, 96 and 97 for effecting rotation of the cam plate 93 and the consequent rotation of the lever 41 also pinned to the cam shaft. The cam slots 95, 96 and 97 are so contoured as to effect during a complete movement of the thumb lever 86, the functions heretofore described. Thus, during movement of the cam follower 98 in the cam slot 95 the parts of the thread guide and holding means A are relatively slidably moved to effect the crossing of the threads s' and s^2 , the clamping of the thread s' and the spreading of these threads apart to permit the movement therebetween of the bills of the tying bill mechanism C. The cam slot 96 is so contoured as to be concentric with the pivot of the thumb lever 86, this to the end of preventing any further movement of the parts of the mechanism A after thread crossing and clamping operations and during the period of rotation of the tying bill mechanism C through substantially 310 degrees. After the tying bill mechanism C has been rotated through about 310 degrees the parts of the mechanism A are moved substantially as a unit, as heretofore referred to, for effecting stripping of the threads from the tying bill mechanism C and during this movement the cam follower 98 cooperates with the cam slot portion 97 of the cam plate 93. Also, during this latter motion the thread s^2 is clamped in the guide slot 45, the parts being so arranged as to permit a small amount of slideable movement of the guide arm 39 and the thread engaging member 40 up to the end of the guide slot 50.
- For effecting the compound movement of the auxiliary cutter D heretofore referred to the cam plate 84 is provided with the cam slot portions 99 and 100, the former being concentric with the pivot shaft of the thumb lever 86 and cooperating with the cam portions I provide the cam follower 101 secured to the end of the fork member 91 of the operating arm 89. The concentric cam slot portion 99 is made of a length to permit a movement of the thumb lever 86 to effect the rotation of the tying bill mech-

anism C throughout an angle of substantially 310 degrees prior to operation of the auxiliary cutter D, Figure 9 of the drawings showing the relative arrangement of the parts after the tying bill mechanism C has been rotated through substantially this angle. In the further movement of the thumb lever 86 the cam follower 101 engages the cam portion 100 of the cam plate 84, the cam plate 84 being rotated to effect the movement of the shearing and clamping jaw 78 first forwardly and then about the fulcrum 79. Simultaneously with the forward part of the movement of the cutting and clamping jaw 78 the cam follower 101 engages the cam track 82 of the clamping blade 76, cooperation between these parts effecting the movement of the clamping blade 76 forwardly simultaneously with the movement of the cutting and clamping jaw 78, the cutting mechanism D being thereby brought into the seat of action between the tying bill mechanism C and the mechanism B for engaging the thread s' . The auxiliary cutter D is furthermore so arranged between the tying bill mechanism C and the mechanism B as to effect the cutting of the strand s' at a point to yield substantially equal thread ends of the strands beyond the knot formed therein. During the cutting activity of the auxiliary cutter D the thread engaging arm 62 of the mechanism B is preferably given a further movement to effect the clamping of the end of the thread s' to permit effective cutting. To this end the cam slot 72 in the member 62 is contoured to provide a slight upward movement of the member 62 during cutting activity, comparison of Figures 9 and 12 of the drawings further showing how the thread engaging finger 67 moves with relation to the thread guide 65.

The use and operation of my knotter will, in the main, be apparent from the above detailed description of the structure and operation thereof. It will be apparent that the knotter may be attached to the left hand of the operator, as shown in Figure 1 of the drawings, the thumb lever 86 being under the control of the thumb of the operator's hand. With the knotter so arranged on the hand the threads s' and s^2 may be laid across the same, the ends of the said threads being held in the right hand of the operator. The threads are arranged in the guides of the mechanisms A and B with the threads in substantially parallel relation and the bills of the tying bill mechanism C arranged therebetween. This manner of threading the knotter has been found very simple and efficacious. During the threading the thread s' is guided by the guides 63, 64 and 65 to crossed position as shown in Figure 8 of the drawings. Figures 4 and 5 of the drawings show the relative arrangement of the parts

in normal or inoperative position. As the thumb lever 86 is first moved downwardly the parts of the thread guide and holding means A are relatively moved to a position as shown in Figure 6 of the drawings, this being obtained substantially prior to the rotation or operation of the tying bill mechanism C. In actual use the tying bill mechanism C may be rotated about 90 degrees, as shown in Figure 8 of the drawings. During this movement of the thumb lever 86 the thread engaging arm 62 is moved with respect to the thread guide head 61 to engage and confine the threads in the thread guide and holding means B, the arrangement of the parts here being shown in Figure 7 of the drawings. In the further movement of the thumb lever 86 the mechanisms A and B are retained in the position shown in Figures 6 and 8 of the drawings and the tying bill mechanism C is rotated to effect the looping of the threads thereon, the operating parts of the mechanism to effect this rotation being shown in Figure 9 of the drawings; and the operated parts with the looped threads thereon in Figure 10 of the drawings. In the still further movement of the thumb lever 86 after the positions assumed as shown in Figures 9 and 10 of the drawings, the mechanism A is moved for knot forming, tightening and stripping operation while simultaneously the tying bill mechanism C is given the last 45 degrees of its motion and the auxiliary cutter D is moved into active position for cutting and clamping the thread engaged thereby, this being shown in Figures 11, 12 and 13 of the drawings. Upon release of the thumb lever 86 the torsion spring 88 effective on the operating arm 89 returns all the parts to their normal or inoperative position, the knotted strands being released by the clamping mechanism A, the resulting knot formation obtained being shown in Figure 14 of the drawings, this being the weaver's form of knot.

From the foregoing it will be apparent that I have provided a knotting device preferably in the form of a hand operated knotter which may, however, be any automatic knotting means not necessarily in the form of a hand operated knotter, in which the parts are relatively few in number compared with the manifold functions involved and in which the said parts are arranged for effective cooperation for forming and tying a weaver's knot on strands threaded on the knotter in a very simple manner. It will be further apparent that numerous changes may be made in the mechanism provided without departing from the spirit of the invention. For example, instead of crossing the threads by the guide means in the thread guide and holding means B, I may provide additional means for crossing the said threads similar to the crossing means pro-

vided in the said guide and holding means A. Moreover, the crossing of the threads at the spaced points x' and x^2 may be effected either simultaneously or alternately. As a further modification it will be apparent that I may provide independent stripping means for stripping the threads from the tying bill mechanism C. Other numerous changes may obviously be made without departing from the spirit of the invention, defined in the following claims.

I claim:

1. In a knot tying mechanism, in combination, a tying bill having thread cutting and clamping means, means for positioning a plurality of strands relative to the tying bill so that the tying bill is between the strands and the strands are crossed at a side of the tying bill and mechanism for operating the tying bill in relation to said strands.

2. In a knot tying mechanism, in combination, a tying bill having thread cutting and clamping means, means for positioning a plurality of strands relative to the tying bill so that the tying bill is between the strands and the strands are crossed on opposite sides of the tying bill and mechanism for operating the tying bill in relation to said strands.

3. In a knot tying device, in combination, a tying bill having thread cutting and clamping means, means for positioning a plurality of strands relative to the tying bill so that the tying bill is between the strands and the strands are crossed on opposite sides of the tying bill and mechanism for moving the tying bill first between the crossed strands on one side and then between the crossed strands on the other side with one of the crossed strands on the said other side grasped by the tying bill for threading through the loop formations in the tying bill formed during its movement.

4. In a knot tying device, in combination, a tying bill, means for receiving a plurality of strands in substantially parallel relation and positioning the same relative to the tying bill with the tying bill therebetween, means for crossing the strands on one side of the tying bill and mechanism for operating the tying bill in relation to the said strands.

5. In a knot tying device, in combination, a tying bill, guides on opposite sides of the tying bill adapted to receive strands in substantially parallel relation, means for crossing the said strands and mechanism for operating the said tying bill in relation to the said crossed strands.

6. In a knot tying device, in combination, a tying bill, means for positioning a plurality of substantially parallel strands relative to the tying bill with the tying bill therebetween; the said means including

guides arranged for crossing the strands on one side of the tying bill, means for crossing the strands on the opposite side of the tying bill and mechanism for operating the tying bill in relation to the said crossed strands.

7. In a knot tying device, in combination, a tying bill, means for positioning a plurality of substantially parallel strands relative to the tying bill with the tying bill therebetween; the said means including guides arranged for crossing the strands on one side of the tying bill, means for crossing the strands on the opposite side of the tying bill and mechanism for moving the tying bill first between the crossed strands on one side and then between the crossed strands on the other side with one of the crossed strands on the said other side grasped by the tying bill for threading through the loop formations in the tying bill formed during its movement.

8. In a knot tying device, in combination, a rotatable tying bill having thread cutting and clamping means, means for positioning a plurality of strands relative to the tying bill so that the tying bill is between the strands and the strands are crossed to the side of the tying bill and mechanism for rotating the tying bill in relation to the said strands.

9. In a knot tying device, in combination, a rotatable tying bill having thread cutting and clamping means, means for positioning a plurality of strands relative to the tying bill so that the tying bill is arranged between the strands and the strands are crossed at a side of the tying bill and mechanism for rotating the tying bill through the crossed strands on said side thereof and in position to grasp one of the strands on the other side thereof, further rotation of the tying bill permitting threading of the said grasped strand through the loop formations on the tying bill to obtain a weaver's knot.

10. In a knot tying device, in combination, a rotatable tying bill having thread cutting and clamping means, means for positioning a plurality of strands relative to the tying bill so that the tying bill is between the strands and the strands are crossed at opposite sides of the tying bill and mechanism for rotating the tying bill in relation to the said crossed strands.

11. The method of tying a weaver's knot which consists in crossing two strands at separated points, in twisting one strand 180 degrees about one crossing to provide a loop with the second strand threaded through the loop, in then twisting the second strand 180 degrees to form a second loop while rotating the first loop through 180 degrees and in then threading an end of a strand located beyond the second crossing through the said loops.

12. The method of tying a weaver's knot which consists in arranging two strands in substantially parallel relation, in crossing the said two strands at separated points, in looping one strand at one crossing with the second strand threaded therethrough, in then twisting the said loop 180 degrees while simultaneously looping the second strand and in then threading an end of a strand located beyond the second crossing through the said loops.

13. The method of tying a weaver's knot which consists in positioning strands arranged in parallel relation with one strand below and the other strand above a tying bill mechanism, in then crossing the strands at opposite sides of the tying bill mechanism and in rotating the tying bill mechanism first through the crossed strands at one side and then through the crossed strands at the other side to provide loop formations in the strands and in then threading one of the strands through the said loops.

14. In a knot tying device, in combination, means for supporting two threads or strands crossed at two spaced points and mechanism for looping one of the strands about the other at one crossed point, twisting the loop, looping the other strand and threading the end of a strand beyond the second crossing through the loops.

15. In a knot tying device, in combination, means for receiving two separated strands, provisions for crossing the strands at two spaced points and mechanism for looping one of the strands about the other at one crossed point, twisting the loop, looping the other strand and threading the end of a strand beyond the second crossing through the loops.

16. In a knot tying device, in combination, means for supporting two threads or strands crossed at spaced points and mechanism for operating on the strands so crossed for producing a weaver's knot, the said mechanism including a tying bill having cutting and clamping means.

17. In a knot tying device, in combination, a tying bill mechanism having cutting and clamping means and means for positioning a plurality of strands to be acted upon by the tying bill mechanism to produce a knot, the said means including mechanism for crossing the strands at one side of the said tying bill mechanism.

18. In a knot tying device, in combination, a tying bill mechanism, guide means for receiving a plurality of separated strands in parallel relation with the strands positioned on opposite sides of the tying bill mechanism to be acted upon by the latter to produce a knot and means for crossing the strands at one side of the said mechanism.

19. In a knot tying device, in combina-

- tion, a tying bill mechanism, means for positioning a plurality of strands to be acted upon by the tying bill mechanism to produce a knot, and means for crossing the 5 strands and spreading the same at one side of the said mechanism.
20. In a knot tying device, a bill, a thread guide for receiving separated threads or strands and positioning the same on opposite sides of the bill and means for effecting relative motion of the strands in said 10 guide for crossing the same.
21. In a knot tying device, a bill, a thread guide element for receiving two strands or 15 threads, and positioning the same on opposite sides of the bill and means for engaging one of the threads in the guide element and for moving the same to cross the other thread.
- 20 22. In a knot tying device, a thread guide element for receiving two strands or threads, a thread engaging member arranged for engaging one of the threads in said guide element and means for moving the element and 25 member in opposite directions to cross the threads and spread them apart.
23. In a knot tying device, a thread guide element for receiving two strands or threads and means for engaging one of the threads 30 in the guide element and for moving the same to cross the other thread, the said means comprising a clamping member co-operating with the guide element for clamping the thread engaged.
- 35 24. In a knot tying device, a thread guide element for receiving two strands or threads, a thread engaging member arranged for engaging one of the threads in said guide elements and means for moving the element and member in opposite directions to cross the threads and spread them apart, the said member comprising a clamping means cooperating with the guide element for clamping the thread engaged.
- 40 25. In a knot tying device, in combination, a knot forming mechanism, a thread guide element on one side of the said knot forming mechanism, the thread guide element including guides for receiving a plurality of separate strands and guiding the 45 same into crossed relation.
26. In a knot tying mechanism, in combination, a tying bill having cutting and clamping means, means for positioning a plurality of strands relative to the tying bill so that the tying bill is between the strands and the strands are crossed at a side of the tying bill, means for operating the tying bill in relation to the strands to produce a loop formation therein and provisions for tightening and stripping the loop 55 formation from the bill.
- 60 27. In a knot tying mechanism, in combination, a tying bill having cutting and clamping means, means for positioning a plurality of strands relative to the tying bill so that the tying bill is between the strands and the strands are crossed at a side of the tying bill, mechanism for operating the tying bill in relation to the strands, the bill being operative to cut and clamp one of the strands and an auxiliary cutter for cutting and clamping the other of the strands.
28. In a knot tying mechanism, in combination, a tying bill having thread cutting and clamping means, means for positioning a plurality of strands relative to the tying bill so that the tying bill is between the strands and the strands are crossed on opposite sides of the tying bill, mechanism for operating the tying bill in relation to said strands to produce loop formations therein and means for tightening and stripping the loop formation from the bill. 75
29. In a knot tying device, in combination, a tying bill having thread cutting and clamping means, means for positioning a plurality of strands relative to the tying bill so that the tying bill is between the strands and the strands are crossed on opposite sides of the tying bill, mechanism for operating the tying bill in relation to said strands to produce loop formations therein and means for tightening and stripping the loop formation from the bill. 80
30. In a knot tying device, in combination, a tying bill having thread cutting and clamping means, means for positioning a plurality of strands relative to the tying bill so that the tying bill is between the strands and the strands are crossed on opposite sides of the tying bill, mechanism for moving the tying bill first between the crossed strands on one side and then between the crossed strands on the other side with one of the crossed strands on the said other side grasped by the tying bill and threaded through the loop formations in the tying bill formed during its movement and means for tightening and stripping the loop formations from the bill to form a weaver's knot. 90
31. In a knot tying device, in combination, a tying bill, means for receiving substantially parallel strands and positioning the same relative to the tying bill with the tying bill therebetween, means for crossing the strands on one side of the tying bill, mechanism for operating the tying bill in relation to the said strands to produce loop formations therein and means for tightening and stripping the loop formations from the bill. 100
32. In a knot tying device, in combination, a tying bill, guides on opposite sides of the tying bill adapted to receive strands in substantially parallel relation, means for crossing the said strands, mechanism for operating the said tying bill in relation to the said crossed strands to produce loop formations therein and means for tightening and stripping the loop formation from the bill. 110
33. In a knot tying device, in combination, a rotatable tying bill having thread cutting and clamping means, means for positioning a plurality of strands relative to the tying bill so that the tying bill is between the strands and the strands are crossed to the side of the tying bill, mech- 115
- 120
- 125
- 130

- anism for rotating the tying bill in relation to the said strands to produce loop formations therein and means for tightening and stripping the loop formation from the bill.
33. In a knot tying mechanism, in combination, a tying bill having cutting and clamping means, means for positioning a plurality of strands relative to the tying bill so that the tying bill is between the strands and the strands are crossed on opposite sides of the tying bill, mechanism for operating the tying bill in relation to said strands, the bill being operative to cut and clamp one of the strands and an auxiliary cutter for cutting and clamping the other of the strands.
34. In a knot tying device, in combination, a tying bill having cutting and clamping means, means for positioning a plurality of strands relative to the tying bill so that the tying bill is between the strands and the strands are crossed on opposite sides of the tying bill, mechanism for moving the tying bill first between the crossed strands on one side and then between the crossed strands on the other side with one of the crossed strands on the said other side grasped by the tying bill and threaded through the loop formations in the tying bill formed during its movement; the bill being operative to cut and clamp the strand grasped thereby and an auxiliary cutter for cutting and clamping the other of the strands.
35. In a knot tying device, in combination, a tying bill having cutting and clamping means, means for receiving substantially parallel strands and positioning the same relative to the tying bill with the tying bill therebetween, means for crossing the strands on one side of the tying bill, mechanism for operating the tying bill in relation to the said strands, the bill being operative to cut and clamp one of the strands and an auxiliary cutter for cutting and clamping the other of the strands.
36. In a knot tying device, in combination, a rotatable tying bill having cutting and clamping means, means for positioning a plurality of strands relative to the tying bill so that the tying bill is between the strands and the strands are crossed to the side of the tying bill, mechanism for rotating the tying bill in relation to the said strands, the bill being operative to cut and clamp one of the strands and an auxiliary cutter for cutting and clamping the other of the strands.
37. In a knot tying mechanism, in combination, a tying bill having cutting and clamping means, means for positioning a plurality of strands relative to the tying bill so that the tying bill is between the strands and the strands are crossed at a side of the tying bill, mechanism for operating the tying bill in relation to said strands, the bill being operative to cut and clamp one of the strands and an auxiliary cutter for cutting and clamping the other of the strands.
38. In a knot tying device, in combination, a tying bill mechanism having cutting and clamping means, thread guides on opposite sides of the tying bill mechanism, each for receiving a plurality of separate strands and an auxiliary cutter between the tying bill mechanism and one of the guides.
39. In a knot tying device, in combination, a tying bill mechanism having cutting and clamping means, thread guides on opposite sides of the tying bill mechanism having means to receive a plurality of parallel separated strands and an auxiliary cutter between the tying bill mechanism and one of the guides for operating on one of the strands.
40. In a knot tying device, in combination, a tying bill mechanism having cutting and clamping means, thread guides on opposite sides of the tying bill mechanism, each for receiving a plurality of separate strands and an auxiliary cutter between the tying bill mechanism and one of the guides and a knot stripping mechanism.
41. In a knot tying device, in combination, a tying bill having cutting and clamping means, thread guide means and a stripping mechanism arranged on one side of the bill, a second thread guide means and an auxiliary cutter arranged on the opposite side of the bill, the auxiliary cutter being located between the bill and the said second guide means.
42. In a device of the class described, a knot forming mechanism and means for positioning a plurality of strands relatively to the knot forming mechanism; the said means including unitary mechanism for crossing the strands and for stripping the same from the knot forming mechanism.
43. In a device of the class described, a knot forming mechanism and means for positioning a plurality of strands relatively to the knot forming mechanism; the said means including a thread guide element, a thread engaging member and means for moving the element and member for crossing the strands, clamping them and stripping the same from the knot forming mechanism.
44. In a device of the class described, a knot forming mechanism, guide means for receiving a plurality of threads to be operated upon by said knot forming mechanism, a thread engaging member cooperating therewith, means for relatively moving the guide means and the said member to effect

crossing of the threads and clamping thereof and means for moving the said guide means and member to effect stripping of the formed knot from the said knot forming member.

45. In a device of the class described, a thread guide arm having means for spacedly receiving two threads, a thread engaging member, means for relatively moving the 10 arm and member to cross the threads and to clamp one of the threads and means for subsequently moving the said guide arm and member for clamping the other thread and for stripping both of the clamped threads.

46. In a device of the class described, a thread crossing, clamping and stripping means comprising relatively movable guide means and thread engaging means and provisions for relatively moving the guide 20 means and the thread engaging means for effecting crossing, clamping and stripping of the threads.

47. In a device of the class described, a thread crossing, clamping and stripping 25 means comprising relatively movable guide means and thread engaging means and mechanism for relatively moving the guide means and the thread engaging means for effecting crossing, clamping and stripping 30 of the threads; the said mechanism including a cam having a plurality of cam portions, one for effecting the relative motion of the guide and thread engaging means and another for effecting unitary motion of the 35 said guide and thread engaging means.

48. In a device of the class described, a thread guide means and a thread engaging member associated therewith, means for relatively slidably moving the guide means 40 and the member in opposite directions and means for subsequently rotating the said guide means and member as a unit.

49. In a knot tying device, a rotatable tying bill including a helix for rotating the 45 same, means for positioning a plurality of threads relatively to the said bill, said means including relatively movable guide members on one side of the bill and cam means for operating the same, an auxiliary 50 cutting device arranged on the opposite side of the bill, cam means for operating the said cutting device and mechanism for effecting operation of the tying bill, the guide members and the cutting device; said mechanism 55 including a forked lever straddling the thread of the helix and provided with means for actuating the said cam means.

50. In a knot tying device, a rotatable tying bill, thread positioning means including thread guide means arranged on one 60 side of the bill, an auxiliary cutter arranged between the tying bill and the thread guide means; the said auxiliary cutter being normally out of alinement with the bill and 65 guide means, means for rotating the tying

bill and means for subsequently advancing the cutting means in alinement with the bill and guide means for cutting operation.

51. In a knot tying device, in combination, a knot forming mechanism including 70 a cutting and clamping bill, means for positioning two strands, one above and the other below the knot forming mechanism with the strands crossed on opposite sides of the said mechanism and means for operating the said knot forming mechanism in relation to the said strands to tie a weaver's knot.

52. In a knot tying device, in combination, a knot forming mechanism, a thread 80 guide element arranged on one side thereof, the said element including guides for receiving a plurality of separated strands and guiding the same into crossed relation, a thread engaging member and means for 85 relatively moving the guide element and the thread engaging member to engage the threads in crossed position.

53. In a knot tying device, in combination, a tying bill mechanism having cutting and clamping means, thread receiving means for receiving two separated strands or threads, the thread receiving means including a guide element located on one side of the said tying bill mechanism, the said tying bill mechanism being operative in its movement for cutting and clamping one of the 90 said threads or strands and an auxiliary cutter between the tying bill mechanism and the said guide element, the said auxiliary cutter having means for cutting and 95 clamping the other of the said strands.

54. In a knot tying device, in combination, a tying bill mechanism having cutting and clamping means, thread receiving means for receiving two separated strands or threads, the thread receiving means including a guide element located on one side of the said tying bill mechanism, the said tying bill mechanism being operative in its movement for cutting and clamping one of the said threads or strands, an auxiliary cutter between the 100 bill tying mechanism and the said guide element, the said auxiliary cutter being adapted to cut and clamp the other of the said strands and comprising cutting and clamping jaws and a cutting and clamping bill movable therebetween.

55. In a knot tying mechanism, a tying bill, means for holding a pair of threads crossed on opposite sides of the tying bill, said means comprising an arm mounted to swing in a direction away from the tying bill and having a pair of thread guides associated therewith.

56. In a knot tying mechanism, the combination with a rotary tying bill, of means for holding and stripping threads to be united, comprising an arm mounted for swinging motion, a second arm mounted to 130

swing with the first mentioned arm and to move longitudinally relative thereto, and a pair of thread guides operatively associated with said arms and occupying in one position of the parts a spaced relation and in another position of the parts a contiguous relation.

57. In a knot tying mechanism, the combination with a rotary tying bill, of means for

- 10 holding two threads crossed on opposite sides of the tying bill, said means including a pair of arms mounted to swing on a common axis away from the tying bill, a pair of thread guides carried by the respective
- 15 arms and means for initially moving one of said arms relative to the other whereby to position the thread guides in co-acting relation and then swinging both of the arms simultaneously, together with said guides, away from the tying bill whereby to strip the loops therefrom.
- 20

58. In a knot tying mechanism, means for holding a pair of threads crossed on opposite sides of a tying bill, said means comprising an arm mounted to swing in a direction away from the tying bill and having

- 25 a pair of thread guides associated therewith, one of said guides being adapted to clamp its thread and the other guide being adapted
- 30 to hold its thread loosely.

59. In a knot tying device, in combination, means for receiving two separated strands, provisions for crossing the strands at two spaced points, and mechanism for looping one of the strands about the other at one crossed point, twisting the loop, looping the other strand and threading the end of a strand beyond the second crossing through the loops.

60. In a device of the class described, the combination with a tying bill, of means to support a pair of strands on opposite sides of the bill, means to engage one strand at opposite sides of the bill and move the engaged portion of the strand across the other strand, mechanism to strain the knot and strip it from the bill, and a common means for the strand moving means, the bill and the stripping mechanism to operate them in sequence.

61. In a device of the class described, a tying bill, means to position the strands for knotting prior to the operation of the bill, including means to move the strands in opposite directions, thereby to cross the strands at opposite sides of the bill.

Signed at Durham in the county of Durham and State of North Carolina this 18th day of February, A. D. 1922.

BRITTON E. BYRD.
